UNITED STATES PATENT OFFICE.

FESTUS S. RAND, OF PROVIDENCE, RHODE ISLAND, ASSIGNOR TO UNIVERSAL WINDING COMPANY, OF PORTLAND, MAINE, A CORPORATION OF MAINE.

WARPING-MACHINE.

1,048,580.

Specification of Letters Patent. Patented Dec. 31, 1912.

Application filed July 1, 1910. Serial No. 569,969.

To all whom it may concern:

Be it known that I, FESTUS S. RAND, a citizen of the United States, residing at Providence, in the county of Providence and State of Rhode Island, have invented certain new and useful Improvements in Warping-Machines, of which the following is a specification.

My invention relates to improvements in warping or beaming machines employed in winding yarn in multiple from creels or other supply stands on to warp- or section-beams, and has for its object to increase the speed of operation of the machine and produce a more perfect beam with the yarn mass disposed concentrically about the axis of the latter.

My invention consists particularly of dogging mechanism adapted to regulate the pressure of the yarn mass on its driving roll or drum so that the beam can be rotated at high speed without vibration or pounding and the yarn wound on more evenly without ridges or eccentric places.

The invention is fully set forth in the following specification, illustrated by the accompanying drawings, in which:

Figure 1 is a front elevation of a usual form of warping or beaming machine, with my improvement shown applied thereto; Fig. 2, a side elevation of the same; Fig. 3, an enlarged, detailed sectional view of the dogging device showing the locking mechanism released; Fig. 4, an end elevation of the same; Fig. 5, a sectional view similar to Fig. 3, with the locking mechanism shown in operative position; Fig. 6, an enlarged sectional elevation showing a modification of the dogging mechanism; Fig. 7, an end elevation of the same.

Figs. 1 and 2 illustrate a usual form of warping or beaming machine adapted for winding yarns in multiple from a creel or other supply-holder on to a warp- or section-beam. The machine consists essentially of two upright frames A at either end, carrying suitable bearings *a* in which the driving-shaft C is rotatably mounted. The shaft C carries a driving-roll or drum D arranged between the two end frames of the machine and adapted to bear on the barrel *b* of the beam B to rotate the latter by

frictional contact with the yarn wound thereon. The beam B consists of the cylindrical barrel *b* having flanges *b'* at either end and provided with trunnions *b''* which rotate in the bushings *b'''* fixed in the ends of the two swinging arms *b''*. The arms *b''* are hinged on a rod *b'''* extending between the end frames of the machine, and weights *b''''*, depending from the ends of the arms, serve to keep the beam in contact with the driving-drum D, see Fig. 2. The warp yarn *y* is led on to the beam, as shown in Fig. 2, and as it is wound on to the barrel *b* the beam rises and the arms swing upward, as indicated by the dot-and-dash lines, which illustrate the beam as nearly filled. The beam B which resembles a spool in form and purpose is subject to hard usage in shipment and handling and is generally so irregular in form and balance that the barrel and heads are not concentric to the gudgeons on which the beam rotates. These latter are sometimes bent out of alignment so that the beam will not run true, and when used in the warping machine the beam will have an uneven bearing on the driving drum. This causes the beam to rise and fall irregularly on the drum, owing to the eccentricity of the barrel, and when the beam is rotated at a high rate of speed it will jump and pound so that the yarn is matted down and wound on hard in some places, while at other places the winding will be soft. This causes an uneven, eccentric disposition of the yarn mass about the axis of the beam, and the ends will not deliver with uniform tension in unwinding. Furthermore, this eccentricity of the yarn mass about the axis of the beam causes uneven strain on the separate yarns in unwinding, which results in weakening the yarn and causing frequent breaks. As explained in the patent to Simon W. Wardwell for warping machine, No. 833,989, issued October 23rd, 1906, it is desirable to control and regulate the pressure of the beam on the driving drum to prevent this vibration and pounding and secure a more perfect and even disposition of the yarn mass about the axis of the beam.

The purpose of the invention disclosed herein is similar to that of the device de-

scribed in the patent above referred to, and the present improvement contemplates means for controlling the movement of the beam toward and away from the driving drum arranged to apply the dogging action at points near the axis of the drum so that it will be more effective in regulating the movement of the drum on its swinging arms.

As shown in Figs. 1 and 2, I provide suitable bearings or standards G which are preferably fastened to the floor between the end frames of the warping machine. Secured in these bearings is a horizontal rod or shaft H, held by the set screws f', see Fig. 2, and mounted on the ends of this shaft are two upright, swiveled staves or rods F held in the arms f which are pivoted on the shaft. The rods F extend upward adjacent the gudgeons of the beam B, and the bushings b³, which serve as bearings for the beam, are secured in brackets E which slide on the rods F. The brackets E are formed with sockets for the bushings b³ and the latter are held in place by the pins e, as illustrated in Fig. 3. At the lower end of each bracket E is an opening or slot e² in which is located a dogging-member I which surrounds the rod F. The rod F is preferably of square section and the member I has a square bore i which is slightly larger than the dimensions of the rod. This bore runs straight through the member, and a second square hole i² is formed in the nut at an angle to the hole i. This second bore or hole i² is of less width than the thickness of the rod F, so that when the member is tipped or canted the sides of this hole will impinge upon the rod and give a wedging grip on the latter. Preferably, the top and bottom sides of the member I are rounded off at i³ and i⁴ so that the member will rock easily on its bearing against the sides of the slot in the bracket E. At the lower end of the bracket E is a pocket e³ in which is located a sliding plunger J, the upper end of which bears on one side of the lower face of the member I. A coiled spring j, held between the head of the plunger and a pin k, serves to force the plunger upward to tend to raise one side of the member I and cramp it into position to impinge upon the rod F, as shown in Fig. 5. Extending through the bracket E is a pin or stud L which carries a cam l adapted to bear on the upper face of the member I. The stud L is operated by a finger pin l' which serves as a lever to turn the cam l down against the member I, to hold the latter against the action of the spring plunger J, as shown in Fig. 3.

The operation of the above described arrangement is as follows: The bushings b³ are placed on the gudgeons b² of the empty beam and slid into the bearings at the ends 65 of the arms b⁴. The brackets E are next

slid up on the rods F and the rods swung outward to adapt the brackets to fit around the bushings. The bushings are then secured in position in the brackets by means of the pins e. The cam l is turned down onto the member I to release the latter from engagement with the rod F so that the bracket E can be adjusted up and down the rod. When the beam is in position the cam l is disengaged from the member I by turning the lever l' and the plunger J will then act to tilt the member I and cause it to bind on the rod F. As the yarn is wound on to the barrel of the beam B the latter will rise on its arms b⁴, and the brackets E adapt themselves to this movement by sliding upward on the rods F. It will be seen that upward movement of the bracket E tends to straighten the position of the member I on the rod F so that the bracket is allowed to slide freely. Movement of the bracket E in the opposite direction, however,—that is, downward on the rod—will be resisted by the member I, because such movement tends to augment the effect of the plunger J to cramp the member against the rod. In other words, with the device adjusted as shown in Fig. 5 the bracket E is free to move upward on the rod F but is prevented from downward movement by the dogging action of the member I. The pivotal mounting of the staves or rods F on the standards G provides for a tilting movement of the rods to accommodate the brackets E to the aernal movement of the bearings of the beam B on its arms b⁴. The effect of this action on the beam B is to prevent it from returning toward the driving drum D after it has once been carried upward. It will be seen that if the barrel of the beam is eccentric or out of true, the latter will rise to accommodate the high place on its periphery, and under ordinary circumstances the beam would fall again after the high place had passed the drum. 110 With the present arrangement the beam is held from moving back toward the drum after it has once been raised, and this action has a tendency to regulate the laying of the yarn so that the mass will be wound more 115 nearly concentric about the axis of the beam. The effect will be to relieve the pressure of the weights b⁶ on the beam when the winding is being done on a low place on the periphery of the mass; but vice versa, when a high place on the periphery is bearing on the driving drum the weights will act with their utmost force. In this way the high places, that is, the places of greatest 120 distance from the axis of the beam, will be 125 pressed down and wound more compactly, while on the low places the pressure is removed so that the yarn will not be wound so hard, and will therefore build up more nearly to the true circumference of the 130

whole mass. The dogging action further prevents the jumping and pounding of the beam on its driving drum, and as the beam is wound more nearly true, peripherally, 5 its speed of rotation can be maintained at a higher rate and therefore the production of the machine is materially increased.

In Figs. 6 and 7 is shown a modification of the dogging mechanism proper, which 10 acts in substantially the same manner as that described above and produces the same effect. At the lower end of the bracket E is a vertically disposed slot e^5 in which is positioned a cam M mounted on the stud or 15 shaft N, and secured by the set screw m. The stud N is mounted rotatively in bearings in the bracket E, and at one of its ends is secured a weighted lever O which serves as a handle for operating the cam M. The 20 face of the cam is adapted to impinge on the side of the rod F and the weighted lever O serves to effect a binding engagement between the cam and the rod. With the parts in position as shown by the dot-and-dash 25 lines in Fig. 6, the bracket E is free to be moved downward on the rod F to adjust it to a position to receive the bushing of the un- 30 filled beam. After the beam is in place with its bearings in the arms b^4 and the bushings 35 b^3 secured in the brackets E the levers O are swung over to the position illustrated by full lines in Fig. 6. With the cams M in this position the upward movement of the 40 brackets E will be unrestricted, but downward movement will be prevented by the effect of the cams binding against the rods F. In this way the cams M serve the same purpose as the members I in the previously described arrangement, and the beam is prevented from vibrating up and down and 45 pounding on its driving drum.

It will be seen that my improved device provides a simple and efficient means for controlling the movement of the beam away 45 from its driving drum to prevent undue vibration or pounding of the beam and to provide for winding on the yarn in a concentric mass. The present arrangement shows meritorious improvement in that the dogging action 50 is applied on both ends of the beam at points adjacent the bearings of the latter, so that the beam is held more positively and rigidly and there is no chance for play. Furthermore, the dogging mechanism is convenient 55 of access and the locking device can be released by simply turning a small finger lever so that the beam can be placed in position and removed very readily and expeditiously.

60 It will be evident that various modifications might be made in the structure and arrangement of my improved device without departing from the spirit and scope of the invention.

65 Therefore without limiting myself to the

precise form and arrangement shown, what I claim is:

1. In a warping- or like machine, the combination with the yarn-beam, of a driving-drum therefor, bearings for supporting the beam to move away from the drum, upright staves extending adjacent the bearings, and automatically operated means connected to the bearings and normally acting on the staves to frictionally grip the latter and prevent movement of the beam toward the driving-drum. 70

2. In a warping- or like machine, the combination with the yarn-beam, of a driving-drum therefor, bearings for supporting the beam to move away from the drum, staves extending upward adjacent the bearings of the beam, automatically operated dogging mechanism connected to said bearings and frictionally gripping the staves to normally prevent movement of the beam toward the drum, and means to release said dogging mechanism. 80

3. In a warping- or like machine, the combination with the yarn-beam, of a frictional driving-drum therefor, means to support the beam to move away from the drum, staves extending adjacent said means, and automatically operated dogging mechanism acting on the staves to frictionally grip the latter and normally prevent the movement of the beam toward the drum. 90

4. In a warping- or like machine, the combination with the yarn-beam, of movable bearings for supporting the beam, a driving-drum arranged to rotate the beam by frictional contact with the yarn wound thereon, brackets connected to the beam bearings, staves on which the brackets slide longitudinally, and automatically operated dogging means on said brackets adapted to normally engage the staves to frictionally grip the latter and prevent movement of the beam toward the driving-drum. 100

5. In a warping- or like machine, the combination with the yarn-beam, of a driving-drum arranged to rotate the beam by frictional contact with the yarn wound thereon, bearings for supporting the beam to move away from the drum, upright staves extending adjacent the bearings, brackets secured to the bearings and arranged to slide on the staves, dogging-members on said brackets adapted to normally engage the staves to prevent the downward movement of the brackets and means to operate said dogging-members. 115

6. In a warping- or like machine, the combination with the yarn-beam, of a frictional driving-drum therefor, bearings for supporting the beam to move away from the drum, brackets adapted to receive said bearings, swiveled staves extending through said brackets, dogging means on said brackets adapted to normally impinge on the staves 125

130

to prevent movement of the beam toward the drum, and resilient means to operate the dogging means to engage the staves.

7. In a warping- or like machine, the combination with the yarn-beam, of a driving-drum therefor, bearings for supporting the beam to move away from the drum, brackets E connected to said bearings, a horizontal shaft H, arms swiveled on said shaft, staves 10 extending upward from the arms, and dogging means on the brackets adapted to be held in engagement with the staves to normally prevent movement of the bearings downward on the staves.
- 15 8. In a dogging-mechanism for warping- or like machines, the combination with the yarn-beam and driving-drum therefor, of a movable bearing for the beam, a bracket connected to said bearing, an upright staff 20 on which the bracket slides, a dogging-member in the bracket having a bore adapted to receive the staff and formed with a second smaller bore inclined to the first bore, and means to cramp the dogging-member to bind 25 on the staff to prevent movement of the bracket in one direction on the staff.
9. In a dogging-mechanism for warping- or like machines, the combination with the yarn-beam and driving-drum therefor, of 30 a movable bearing for the beam, a bracket secured to said bearing, an upright staff on which the bracket slides, a dogging-member in the bracket having a straight bore to receive the staff and a second bore inclined 35 thereto, a plunger adapted to press on one

side of the dogging-member to cramp the latter into binding engagement with the staff, and a spring to operate the plunger.

10. In a dogging-mechanism for warping- or like machines, the combination with the 40 yarn-beam and driving-drum therefor, of a movable bearing for the beam, a bracket connected with said bearing, an upright staff on which the bracket slides, a dogging-member in said bracket engaging the staff and 45 adapted to be cramped thereon to provide a wedging grip to hold the bracket, means to cramp the dogging-member on the staff, and means to hold the dogging-member against the cramping means to allow the bracket to 50 slide on the staff.

11. In a dogging-mechanism for warping- or like machines, the combination with the yarn-beam and driving-drum therefor, of 55 a sliding bracket having a bearing for the beam, a staff on which the bracket slides, a dogging-member in said bracket adapted to be cramped against the staff to prevent movement of the bracket in one direction, means to cramp the dogging-member, and 60 a cam adapted to be engaged with the member to oppose said cramping means to allow the member and bracket to slide on the staff.

In testimony whereof I affix my signature in presence of two witnesses.
